RACK FOR HANGING GARMENTS OR THE LIKE

Tomihei Saika, 116, 3-chome, Yagumo-Naka-machi,
Moriguchi, Osaka, Japan

Filed Apr. 10, 1972, Ser. No. 242,893

Term of patent 14 years

Int. Cl. D20—02

U.S. Cl. D6—24

FIG. 1 is a perspective view of a rack embodying my new design;

FIG. 2 is a top plan view of the rack of FIG. 1;

FIG. 3 is a bottom plan view of the rack of FIG. 1;

FIG. 4 is a side elevational view of the rack of FIG. 1; and

FIG. 5 is a front elevational view of the rack of the preceding figures.

I claim:

The ornamental design for a rack for hanging garments or the like, substantially as shown.
